UNITED STATES PATENT OFFICE.

ARTHUR E. JONES, OF UNION CITY, CONNECTICUT, ASSIGNOR TO THE S. O. & C. CO., OF ANSONIA, CONNECTICUT, A CORPORATION OF CONNECTICUT.

MACHINE FOR SETTING GROMETS AND SIMILAR ARTICLES.

No. 817,780.

Specification of Letters Patent.

Patented April 17, 1906.

Application filed February 25, 1905. Serial No. 247,323.

To all whom it may concern:

Be it known that I, ARTHUR E. JONES, a citizen of the United States, residing at Union City, in the county of New Haven and State 5 of Connecticut, have invented certain Improvements in Machines for Setting Gromets and Similar Articles, of which the following description, in connection with the accompanying drawings, is a specification, like reference characters on the drawings indicating like parts in the several figures.

This invention relates to machines for attaching to stock gromets, buttons, rivets, and similar articles, with which a washer or 15 analogous device is used, the head of the gromet, button, or rivet after it has been attached lying upon one side of the stock and the washer or analogous device lying upon the other side of the stock and being fastened 20 to a projecting portion of the gromet, button, or rivet. Particularly my invention relates to machines for setting gromets; and the general object of the invention is to provide means for insuring that a gromet and 25 a washer will be fed at each operation of the machine into alinement with the device that upsets the shank of the gromet to fasten it to the washer.

In the embodiment herein shown, which 30 represents the preferred form of my invention, I have provided a well for holding a plurality of washers and constructed to permit the washers to pass therefrom and a device for bearing down upon the washers in the 35 well to force them toward the point at which they pass from the well. Preferably means is provided for supplying washers to the well and also means for separating the lowermost washer in the well from the one above it and 40 removing it from the well.

In the form of my invention herein shown the device which bears upon the washers in the well is actuated intermittently to permit washers to pass into the well.

45 Other features of my invention are improved hoppers for holding the gromets and washers and novel mechanism for actuating the devices which feed the gromets and washers into alinement with the setting device.

50 In the drawings, Figure 1 is a front elevation of a gromet-setting machine embodying features of my invention. Fig. 2 is an elevation of the left-hand side of the machine

shown in Fig. 1. Fig. 3 is an elevation of the right-hand side of the machine shown in Fig. 55 1. Fig. 4 is a plan view, partly in section, taken on the line $x-x$ of Fig. 3. Fig. 5 is a detail perspective view, partly in section, looking from the right-hand side of the rear of the machine, showing the gromets passing from the hopper into the gromet-raceway. Fig. 6 is a detail elevation view of a portion of the gromet-raceway and the gromet-feed slide in its rearward position and also shows the setting device in the operation of upsetting the shank of a gromet. Fig. 7 is a detail elevation view of the parts shown in Fig. 6 with the setting device elevated, the gromet-feed slide in its forward position, and the centering-pin elevated to 70 hold a gromet in position on the anvil. Fig. 8 is a detail perspective view looking from the front of the right-hand side of the machine, showing the mechanism for conveying the washers from the washer-hopper 75 and feeding them into alinement with the setting device. Fig. 9 is a detail elevation view, partly in section, taken through the center of the washer-feed slide and shows the washer-well, a portion of the washer-raceway, and the washer-feed slide in its rearward position. Fig. 10 is a detail elevation view of the parts shown in Fig. 9 with the washer-feed slide in its forward position. Fig. 11 is a perspective view of a gromet 85 and a washer. Fig. 12 is a detail sectional view of a portion of the well and the washer-feed slide, and Fig. 13 is a plan view of a portion of the washer-feed slide.

In the drawings, 2 designates a standard 90 which supports a head 4, provided with a stud 5, on which levers 6 and 7 are mounted, the lever 6 having a rounded end which engages a yoke 8 on the upper end of a setting-device plunger 9, movably mounted in a 95 guideway formed in the head of the machine, and the lever 7 having a rounded end which engages a yoke 10 on the upper end of a plunger 11, movably mounted in a guideway formed in a block 12, adjustably fastened to 100 the head by screws 13. A setting device 14 is carried by the plunger 9, and a punch 15 is carried by the plunger 11, the setting device being adapted to upset the shank of a gromet resting on the cup-shaped anvil 16, formed in 105 the work-supporting table 17, and the punch

being adapted to coöperate with a female die 18 in an adjustable block 19 for forming an opening in the stock to receive the gromet. Pivoted at 20 to the standard are treadles 21 and 22, which are connected by rods 23 and 24 to the levers 6 and 7, so that when said treadles are depressed said levers will be actuated for depressing the punch and the setting device, the treadles and levers being returned to normal position by springs 25 and 26, fastened to the standard and to collars 27 and 28 on the rods, as shown in Fig. 2.

A gromet-hopper comprising a tray 30 and a cover 31 is oscillatingly mounted on a shaft 32, supported by brackets 33, connected to the head of the machine, and fastened to an ear 34 on said tray by a universal connection is a link 35, which at its upper end is fastened by a universal connection to the lever 6, said connections comprising blocks 36, pivotally mounted in the forked ends of the link and pivotally connected by pins 37 to said lever and ear. The tray 30 is provided with parallel grooves 40, which in width are equal to the width of the head of a gromet, and in the lower edge of the cover 31 are openings 41, which in width are equal to the diameter of the shank of a gromet, the lower edge of said cover standing above the bottom of the grooves a distance equal to the thickness of the head of a gromet, so that only those gromets which stand on their heads with their shanks projecting upwardly can pass from the hopper. When the lever 6 is rocked, the link 35 will oscillate the hopper, as shown in Fig. 5, so that the gromets will pass through the openings 41 in the lower edge of the cover and drop into the raceway 42, down which they travel, resting on their heads, to the feed-slide, which moves them into alinement with the setting device. The lower end of the raceway 42 terminates a short distance from the work-supporting table 17, so that the head of the lowermost gromet in the raceway will rest upon said table with its shank embraced by spring-fingers 43 at the end of the raceway. The lowermost gromet in the raceway is fed forwardly onto the cup-shaped anvil 16, formed in the work-supporting table, by a reciprocating feed-slide 44, mounted in a guideway 45 on the head of the machine, the front end of said slide being bifurcated at 46 to embrace the shank of a gromet and the rear end of said slide carrying a roller 47, which is engaged at each downward movement of the rod 23 by an inclined face 50 on a block 51, carried by said rod, the feed-slide being moved rearwardly at each upward movement of said rod by a contractile spring 52, connected to a pin 53 on the feed-slide and to a pin 54 on the guideway in which said slide is mounted. When the gromet-feed slide is in its rearward position, its front end is raised from the work-supporting table, as shown in Fig. 6, so that when said slide moves forwardly

its bifurcated end will pass over the flange or head of the lowermost gromet in the raceway. An inclined face 55 on the gromet-feed slide then comes into engagement with a roller 56, which depresses the end of said slide down 70 upon the flange of the gromet, and thereby prevents the gromet from moving out of the control of the feed-slide when it arrives at the end of its forward movement.

A centering-pin 57, fastened to a lever 58, 75 which is pivoted at 60 to the standard, is reciprocatingly mounted in an opening in the work-supporting table in alinement with the center of the anvil 16, as shown in Figs. 6 and 7, and when in its elevated position said pin 80 is adapted to project into the shank of a gromet and hold it on said anvil. The centering-pin is depressed by its engagement with the setting device during the downward movement of the latter and is elevated during the upward movement of the setting device by means of a stop 61, carried by the block 51 and adapted to engage an adjustable stop 62 on lever 58 whenever rod 23 moves downwardly. After a gromet has been fed 90 into position on the anvil and the centering-pin has been elevated to hold said gromet in position the stock, which has been previously provided with a hole to receive the gromet, is moved laterally to place said hole 95 in alinement with the shank of said gromet, and a washer is then fed into alinement with the setting device. The setting device then moves downwardly, forcing the washer down upon the stock, with the shank of the gromet 100 projecting into the opening in the washer, and bending the end of said shank over the edge of the opening in the washer, so that the head of the gromet will lie upon one side of the stock and the washer upon the other side of 105 the stock.

The washers are contained in a hopper comprising a tray 66 and a cover 67, and said hopper is mounted on a shaft 68, that is supported in brackets 69, fastened to the frame 110 of the machine, an oscillating movement being imparted to said hopper by means of a link 70, fastened at one end to the lever 7 and at its other end to an ear on the tray 66, the same as described with reference to the 115 link 35, which actuates the gromet-hopper. As the washer-hopper is oscillated the washers pass into a receiving-raceway 71 in a substantially vertical or upright position, as shown in Fig. 8, and roll on their edges down said raceway to its lower end, which is bent at 72 at substantially a right angle to the main portion thereof, the washers then dropping into the delivery-raceway 73, down which they travel, resting on their bottom 120 faces, to a well 74 at the lower end thereof. The tray 66 is provided with a plurality of grooves 75 of uniform width, and each groove is narrower at the bottom than at the top, so that only those washers which rest on their 125 bottom faces enter the receiving-raceway 71. The tray 66 is provided with a plurality of grooves 75 of uniform width, and each groove is narrower at the bottom than at the top, so that only those washers which rest on their 130 bottom faces enter the receiving-raceway 71.

top faces can pass under the edge of the cover 67, thereby insuring uniformly-positioned washers in the well 74. As shown in Fig. 8, an inclined face guide-bar 76 extends across the end of the tray 66 inside of the cover 67, so that any washers which pass down the grooves in an inverted position will be unable to pass under said bar, and consequently will ride up on the inclined face thereof and fall back into the mass of washers in the hopper, thereby preventing the incorrectly-positioned washers from collecting at the ends of the grooves in the tray. The cover of each hopper has a hinged lid 80, and for preventing too great a flow of gromets and washers gates 81 are adjustably fastened to the covers of the hoppers and are adapted to be moved over the ends of the grooves in the trays.

A washer-feed slide 84, which is mounted in a guideway 85 on the head of the machine, forms the bottom of the well 74 and is adapted to receive the lowermost washer in the well and move it into alignment with the setting device, the front end of said slide being bifurcated and the upper surface being provided with a recess 86, which receives the lowermost washer in the well when the slide is in its rearward position. The washer-feed slide is moved forwardly by means of an actuator 87, mounted in a guideway 88 on the head of the machine, and which is provided at its front end with a slot 89, which engages a pin 90, that contacts with the feed-slide, said actuator having fastened to one side of its rear end a roller 91, which is engaged at each upward movement of the rod 23 by an inclined face 92 on a block 93, carried by said rod, the actuator and washer-feed slide being moved rearwardly as soon as said inclined face has passed out of engagement with said roller by a contractile spring 94, fastened to a pin 95 on the actuator and to a pin 96 on the guideway in which the actuator is mounted. The block 93 is pivotally connected at 97 to a bearing 98 on the rod 23 and is held normally in engagement with an adjustable stop 99 on said bearing by a spring 100, so that when the rod 23 is moving downwardly and the curved face 101 on the block 93 comes into engagement with the roller 91, as shown in dotted lines in Fig. 3, said block will swing on its pivot until the curved face has passed out of engagement with said roller, the block being returned to engagement with the stop 99 by the spring 100, so that when rod 23 again moves upwardly the inclined face on the block 93 will be in position for moving the actuator forwardly.

For insuring that a washer will be removed from the well each time the washer-feed slide moves forwardly I have provided a follower 105, which is actuated intermittently down upon the pile of washers in the well to nest them closely together and force the lowermost washer into the recess 86 in the end of

the feed-slide, and a retainer 107 for separating the lowermost washer in the well from the one above it. The retainer is mounted on the feed-slide and is movable relatively thereto for forcing its end between the lowermost washer and the one above it and for holding said washer in the recess in the slide during the forward movement of the slide.

In order that the well may be kept filled with washers, the follower is withdrawn intermittently to permit the washers to pass from the raceway into the well, and to this end the rod 108, to which the follower is fastened, is provided with a block 109, that is engaged by the lever 6 when it is rocked for moving the setting device upwardly. Preferably the follower is forced yieldingly down upon the washers in the well when the lever is rocked in the opposite direction, and in the preferred form of my invention, as herein shown, this is accomplished by a coiled spring 110, which surrounds said rod between a collar 111 thereon and a stationary part of the frame of the machine, as shown in Fig. 2. The retainer 107 is mounted in a slot in the upper surface of the washer-feed slide and carries the pin 90, which engages the slot in the end of the actuator, said pin projecting downwardly through a slightly-elongated slot 112 in the washer-feed slide, as shown in Fig. 9, so that when the actuator starts to move forwardly the retainer will be moved, but the washer-feed slide will not commence to move until the pin 90 comes into engagement with the front wall of the slot 112, thereby moving the front end of the retainer between the lowermost washer in the well and the one above it and holding said lowermost washer in the recess in the feed-slide. The recess 86 in the washer-feed slide is deeper at its rear end than at its front end, as shown in Fig. 12, and the feed-slide is held yieldingly in contact with the lower end of the walls of the well 74 by springs 114 and 115, the spring 114 being fastened to the guideway in which the slide moves and the spring 115 being fastened to the washer-feed slide. By providing the feed-slide with a recess of this character and holding said slide yieldingly in engagement with the well the edge of the washer at the front end of the recess will be approximately flush with the upper surface of the feed-slide, and the edge of the washer at the rear end of the recess will be overlapped by the retainer, so that when said slide moves forwardly the edge of the washer at the front end of the recess will force its way under the wall of the well, and thus insure the removal of but a single washer at each operation. The retainer holds the washer in the recess while the feed-slide is moving forwardly and also acts as a support for the washers in the well when the feed-slide is in its forward position. For preventing the washers from being displaced

from the feed-slide by the momentum of said slide as it moves forwardly the setting device 14 is yieldingly mounted in the plunger 9, and the movement of said plunger is so timed that the lower end of the setting device will be in the plane of movement of the washer-feed slide when it arrives at the end of its forward movement, so that the washer in said slide will engage the setting device, which to will yield and then snap into the opening in the washer.

For preventing the gromets from becoming jammed in the raceway means is provided for deflecting from the raceway any 15 gromets which enter when the raceway is filled with correctly - positioned gromets. That portion of the gromet - raceway 42 which is adjacent to the gromet - hopper is wide enough to hold only one row of correctly - positioned gromets, which rest on their heads or flanges, so that a gromet which enters the raceway while it is filled with one row of correctly - positioned gromets will roll on the edge of its flange down the raceway until its shank or barrel comes into contact with a deflector 117, fastened to the raceway, as shown in Figs. 1 and 4, said deflector guiding the gromet into a chute 118, fastened to the frame of the machine. The correctly - positioned gromets travel down the raceway until they come into contact with a gate that is moved intermittently to allow a gromet to pass to the end of the raceway.

The gate comprises a head 121, provided 35 with a plurality of fingers 122, that extend over the raceway, and said head is fastened to a shaft 123, mounted in a stationary bearing 124 and provided at its rear end with a ratchet - wheel 126, which is rotated intermittently by a pawl on a pawl-carrier 127. Said pawl - carrier is rotatably mounted on the shaft 123 and is connected to a link 129, having a slot 130, which engages a pin 131 on the lever 6, so that as said lever is rocked for depressing the setting device the link will be moved upwardly to cause the pawl to rotate the shaft on which the gate is mounted. A coiled spring 132, which is confined in the slot 130 between the lower edge thereof and 50 the pin 131, imparts a yielding movement to said link to restore the pawl-carrier to normal position when the lever 6 is rocked in the direction for elevating the plunger.

Sometimes the washers drop into the well 55 in an inclined position, as shown in Fig. 9, and for causing them to assume a horizontal position an agitator 140 is moved intermittently into engagement with the lowermost washer in the well to shake or agitate the pile 60 of washers. The agitator 140 is movably mounted in an opening 141, formed in the work-supporting table under the well, and is connected by a link 142 to the end of a lever 143, fulcrumed at 144 on an ear projecting 65 from the standard and connected by a pin

146 to the lever 58, which operates the centering-pin.

When the machine is at rest, the lever 143 and link 142 will occupy the positions shown in Figs. 3 and 8, and the end of the agitator 70 will be below the surface of the work-supporting table, the link being held in this position by means of a spring 147, connected at one end to a pin on the link and at its other end to a pin on lever 143. A screw 148 in the 75 work-supporting table extends through an elongated slot 149 in the agitator, and when the lever 143 moves downwardly in the direction of the arrow in Fig. 8 said screw will prevent the agitator from moving downwardly, 80 thereby causing the link to be moved into the position shown in Fig. 9 to straighten the toggle formed by said link and agitator. When the lever 143 moves upwardly, the toggle being then straightened, the agitator 85 will move into the position shown in dotted lines in Fig. 9, thereby striking the washers in the well and causing any that are standing in an inclined position to assume a horizontal position. When the lower end of the slot 149 90 comes into contact with the screw 148, further upward movement of the agitator is prevented, thereby breaking the toggle and moving the upper end of the agitator forwardly, the spring 147 returning the link and agitator to 95 normal position with the stop 150 on the link engaging the notch 145 in the agitator.

The operation of the machine is as follows: The stock into which the gromets are to be set is placed on the work-supporting table, 100 and the operator then depresses the treadle 22 to actuate the punch for forming a hole in the stock. The stock is then moved laterally to place the hole in the stock in alignment with the gromet, which is held in position on the anvil by the centering - pin, which is normally elevated, and the operator then depresses both treadles simultaneously to upset the shank of said gromet and also 105 punch a hole for the next gromet that is to be attached to the stock. As the rod 23 moves upwardly the inclined face 50 on block 51 will be moved out of engagement with the roller on the end of the gromet - feed slide, and the spring 52 will move said slide rearwardly. Just as the gromet-slide is moved rearwardly the washer-feed slide is moved forwardly by the engagement of the inclined face 92 on block 93 wth the roller 91 on the feed-slide actuator, and the lowermost washer 110 in the well will be removed therefrom and carried into alignment with the downwardly-moving setting device 14, which forces the washer down around the shank of the gromet and bends the end of said shank over the 115 edge of the opening in the washer. The follower moves downwardly upon the washers in the well at each operation of lever 6 for moving the setting device downwardly and is moved upwardly to permit washers to pass 120 125 130

from the raceway into the well at each operation of said lever for elevating the setting device. My machine therefore comprises automatic means for supplying the well with washers in combination with means for forcing the washers down into the well. As the setting device comes into engagement with the centering-pin said pin is moved below the surface of the work-supporting table to permit the stock to be moved into position to receive the next gromet. When the operator removes his foot from the treadles, the springs return the treadles to normal position, and as the rods 23 and 24 move downwardly the inclined face 50 on block 51 will move the gromet-feed slide forwardly to carry a gromet into alignment with the setting device, and the stop 61 on said block will engage the stop 62 and rock the lever 58 for elevating the centering-pin and moving the agitator into engagement with the pile of washers in the well.

Having described my invention, what I claim as new, and desire to secure by Letters Patent of the United States, is—

- 25 1. In a machine of the class described, a well for holding washers, means for removing a washer from the well, a follower, and means for actuating said follower intermittently to bear upon washers in the well and force them toward the point at which they are engaged by the washer-removing means.
- 30 2. In a machine of the class described, a well for holding washers, a device provided with a recess for receiving the lowermost washer in the well, a follower, means for actuating said follower intermittently to bear upon washers in the well and force said lowermost washer into said recess, and means for actuating said device to remove said lowermost washer from the well.
- 35 3. In a machine of the class described, a well for holding washers, a device mounted below said well for receiving a washer, a retainer mounted on said device and arranged to pass between the lowermost washer in the well and the one above it, and means for actuating said device to remove the lowermost washer from the well.
- 40 4. In a machine of the class described, a well for holding a plurality of washers, a device mounted below said well and provided with a recess for receiving a washer, a retainer mounted on said device and arranged to pass between the lowermost washer in the well and the one above it, and means for actuating said device to remove the lowermost washer from the well.
- 45 5. In a machine of the class described, a well for holding washers, a device mounted below said well and adapted to receive a washer, a retainer mounted on said device, and means for moving the retainer relatively to said device to place the retainer between a washer and those above it in the well and
- 50 for thereafter actuating said device to remove a washer from the well.
- 55 6. In a machine of the class described, a well for holding washers, a follower, means for actuating said follower intermittently to bear upon washers in the well, a device adapted to receive the lowermost washer in the well, a retainer, and means for actuating said retainer to carry its end between the lowermost washer in the well and the one above it and thereafter actuating said device for removing the lowermost washer from the well.
- 60 7. A well for holding washers, a follower bearing yieldingly upon the washers in said well, means for raising said follower intermittently, a device provided with a recess for receiving the lowermost washer in the well, a retainer, moveably mounted on said device, means for actuating said retainer to carry its end between the lowermost washer in the well and the one above it and thereafter actuating said device for removing the lowermost washer from the well.
- 65 8. In a machine of the class described, a well for holding washers, means for removing a washer from the well, means for supplying washers to said well, a follower for bearing upon the washers in the well to force the washers toward the point at which they are engaged by the washer-removing means, and mechanism for raising said follower intermittently to permit washers to pass into the well.
- 70 9. In a machine of the class described, a well for holding washers, means for removing a washer from the well, means for supplying washers to said well, a follower, yielding means for moving said follower downwardly upon the washers in the well to force them toward the point at which they are engaged by said washer-removing means, and mechanism for raising said follower intermittently to permit washers to enter the well.
- 75 10. In a machine of the class described, a raceway for containing washers, a washer-holding well, means for removing a washer from the well, a follower for bearing upon the washers in the well to force them toward said washer-removing means, and mechanism for actuating said follower intermittently to permit washers to pass from the raceway into the well.
- 80 11. In a machine of the class described, a washer-holding well, a device for removing a washer from the well, automatic means for supplying the well with washers, and a follower for forcing the washers down into the well toward the point at which they are engaged by said removing device.
- 85 12. In a machine of the class described, a setting device, a lever for actuating said setting device, a well for holding washers, means for removing a washer from said well, a follower for bearing upon the washers in said well to force them toward said washer-remov-

ing means, and a connection between said follower and lever whereby said follower is actuated when the lever is operated.

13. In a machine of the class described, a well for holding washers, a device provided with a recess for receiving the lowermost washer in the well, means for holding said device yieldingly in engagement with the lower end of said well, and means for actuating said device to remove a washer from the well.

14. In a machine of the class described, a well for holding washers, a device mounted below said well, a recess of varying depth formed in said device for receiving the lowermost washer in the well, means for holding said device yieldingly in engagement with the well, a retainer mounted on said device, and means for actuating said retainer to move its end over the recess in said device and thereafter actuating said device to remove a washer from the well.

15. In a machine of the class described, a raceway for containing gromets, a feed-slide, means for reciprocating said slide to remove a gromet from the end of the raceway, and means for holding said slide down upon the flange of the gromet.

16. In a machine of the class described, a plunger, a setting device yieldingly mounted in said plunger, a feed-slide for moving a washer into alignment with the setting device, and means for actuating said plunger to carry the end of the setting device into the plane of movement of the feed-slide as the washer is moved into alignment with the setting device, substantially as described.

17. In a machine of the class described, a setting device, means for actuating said setting device, hoppers for containing gromets and washers, raceways into which the gromets and washers pass from said hoppers, a well located at the lower end of the washer-raceway for receiving washers passing from said raceway, means for feeding gromets from the gromet-raceway into alignment with the setting device, means for removing washers from said well and carrying them into alignment with the setting device, and means for forcing the washers in the well toward said washer-removing means.

18. In a machine of the class described, a punch and a setting device, levers for actuating said punch and setting device, means for operating said levers, hoppers for containing gromets and washers, means operated by said levers for oscillating said hoppers, raceways into which the gromets and washers pass from said hoppers, a well located at the lower end of the washer-raceway for holding washers, a reciprocating slide for feeding gromets from the gromet-raceway into alignment with the setting device, and a reciprocating slide for feeding washers from said well into alignment with said setting device.

19. In a machine of the class described, a

setting device, a lever for operating said setting device, a rod for actuating said lever, reciprocating slides for feeding gromets and washers into alignment with the setting device, means carried by the rod for reciprocating the washer-feeding slide, and mechanism independent of said last-named means for reciprocating the gromet-feeding slide.

20. In a machine of the class described, a setting device, a lever for actuating said setting device, a device for feeding a gromet into alignment with the setting device, means for moving the gromet-feeding device forwardly, and yielding means independent of said last-named means for moving said feeding device rearwardly.

21. In a machine of the class described, a setting device, a lever for operating said setting device, a rod for actuating said lever, feeding-slides for moving gromets and washers into alignment with the setting device, means actuated by said rod for moving said slides forwardly, and yielding means for moving said slides rearwardly.

22. In a machine of the class described, a washer-feeding slide, an actuator connected to said slide, a reciprocating rod, a block pivotally connected to said rod and adapted to move the actuator in one direction, a stop carried by said rod, means for holding said block normally in engagement with said stop, and means for moving the actuator in the opposite direction.

23. In a machine of the class described, a washer-feeding slide, an actuator connected to said slide and provided with a roller, a reciprocating rod, a block pivotally connected to said rod and provided with an inclined face that is adapted to engage said roller and move the washer-feeding slide forwardly when the rod is moved in one direction, means for moving the washer-feeding slide rearwardly, and an engaging face formed on said block and adapted to contact with said roller for swinging the block on its pivot when the rod is moved in the other direction.

24. In a machine of the class described, a setting device, mechanism for actuating said setting device, means for feeding gromets into alignment with the setting device, a centering-pin for holding a gromet in operative position, a lever to which said pin is connected, and means movable with the setting-device-actuating mechanism for operating said lever.

25. In a machine of the class described, a setting device, a lever for actuating said device, a plurality of hoppers for containing washers and gromets, shafts on which said hoppers are fulcrumed, raceways formed independent of said hoppers and located adjacent thereto for receiving the washers and gromets, a connection between said gromet-hopper and the setting-device-actuating lever whereby movement of said lever will oscil-

late said hopper and cause the gromets to drop into the gromet-raceway, and means for oscillating the washer-hopper to cause the washers to drop into the washer-raceway.

- 5 26. In a machine of the class described, a hopper for containing washers, a receiving-raceway having an inclined vertical passage-way down which the washers roll in a substantially vertical position, and a delivery-raceway having an inclined horizontal passage-way down which the washers travel in a substantially horizontal position, the lower end of the receiving-raceway being bent at an angle to the main portion thereof and located 10 in alinement with the upper end of the delivery-raceway, substantially as and for the purpose described.

- 20 27. In a machine of the class described, a gromet-hopper comprising a tray provided with a plurality of parallel grooves which in width are substantially equal to the diameter of the flange of a gromet, and a cover for said tray which is provided at its lower edge with a plurality of notches in alinement with 25 the grooves in the tray and which in width are substantially equal to the diameter of the shank of a gromet.

28. In a machine of the class described, a well for holding washers and constructed to 30 permit the washers to pass therefrom, a fol-

lower, and means for actuating said follower intermittently to bear upon washers in the well and force them toward the point at which they pass from the well, the well being constructed to admit washers when the follower is withdrawn. 35

29. In a machine of the class described, a well for holding washers and constructed to permit the washers to pass therefrom, automatic means for supplying the well with 40 washers, and a follower for forcing the washers down into the well toward the point at which they pass from the well.

30. In a machine of the class described, a setting device, a well for holding washers 45 means for removing a washer from the well and placing it in alinement with the setting device, a follower, and means for actuating said follower intermittently to bear upon the washers in the well and force them toward 50 the point at which the washers are engaged by said removing means.

In testimony whereof I have signed my name to this specification in the presence of two subscribing witnesses.

ARTHUR E. JONES.
